UNITED STATES PATENT OFFICE.

HEZEKIAH CASEY, OF BIRMINGHAM, ASSIGNOR TO GEORGE HANNA, OF RUSHVILLE, ILLINOIS.

DISK-SHARPENER.

SPECIFICATION forming part of Letters Patent No. 499,907, dated June 20, 1893.

Application filed February 6, 1892. Serial No. 420,571. (No model.)

To all whom it may concern:

Be it known that I, HEZEKIAH CASEY, a citizen of the United States, residing at Birmingham, in the county of Schuyler and State 5 of Illinois, have invented a new and useful Disk-Sharpener, of which the following is a specification.

My invention relates to improvements in disk sharpeners, particularly for disks of the order used in harrows;—and the objects of my invention are, first, to provide a machine of substantial and compact construction and capable of ready manipulation, whereby to cut, at will, and at any desired angle or bevel, 10 either side or both sides of a rotating disk at its peripheral edge to sharpen the said edge; second, to provide a mechanism adapted for being readily applied to cut or shave off a disk's edge at any desired bevel on either 15 side, without checking or stopping the rotary motion of the disk, or without altering the cutting knife or knives, or other cutting tool or tools in a holder or holders; third, to rotate a disk, and, at the same time, hold its 20 edge firmly in position while cutting or shaving and thereby removing portions of its surface to bevel and sharpen the disk's edge; fourth, to provide a mechanism with knives or analogous devices to be actuated by a single lever handle, for cutting, on the opposite 25 sides the rotating disk's edge at predetermined angles, and in succession; fifth, to provide a disk sharpener mechanism with suitable appliances whereby a single lever handle may 30 operate separate knives or analogous devices, applying either knife, at will, on its respective side of a rotating disk; sixth, to provide a compact disk sharpener machine capable 35 of being wholly operated by the attendant, 40 wherein the rotary motion of a disk is imparted by one hand of the operator while his other hand is employed in applying a knife or other analogous device, to the rotating disk; and seventh, to provide a disk sharpener with suitable cutting appliances and 45 means whereby the rotary motion to be imparted to a disk may be given by the operator in charge, or may be produced by steam power or other suitable power mechanism. I attain 50 these objects by the mechanism hereinafter

described and illustrated in the accompanying drawings, in which latter—

Figure 1 is a top plan view of a machine embodying my invention wherein knives are used for cutting, and thereby sharpening the 55 disks as they are one by one rotated by the machine until sharpened. Fig. 2 is a side elevation from the disk side of the machine. Fig. 3 is a similar view from the opposite side of the machine. Fig. 4 is an end elevation, 60 fronting which the attendant is to stand in operating the hand lever actuating the movements of the knives.

Similar letters refer to similar parts throughout the several views. 65

The table or platform A, and its legs or standards B B' constitute the frame work of the machine. A fly wheel C, a belt wheel D and a small spur wheel E are carried upon one end *a* of a shaft F, the other end of the 70 shaft being held on the top of the platform A by a box *a'* securely fastened by bolts *a'* passing into the platform. Meshing with said spur wheel E is a large spur wheel G which latter is fixed upon a shaft H to rotate there- 75 with, said shaft being held in journal boxes *a'* bolted to the top of the platform A. The shaft H, near its opposite end, is provided with a flange I, and the extreme end of the shaft is screw threaded and provided with a 80 nut K and washer *k* said flange I, nut K and washer *k*, together with the screw threaded shaft H serving to form a clamp to hold the disk, as for example, the harrow disk L, securely upon the end of the shaft H and to rotate the same, as the shaft rotates, for the 85 purpose of cutting or otherwise beveling its edge and thereby sharpening it.

A slotted slide M carries a double lever, the long arms N O thereof being connected by a 90 cross-bar P pivotally attached, as clearly shown in the top plan view Fig. 1. The outer end of the arm N is provided with a handle *n*. The said lever arms N O are attached at the point of their intersection to the slotted 95 slide M by means of a nut *m* and bolt *m'*, the said bolt serving as a fulcrum pin. The lever arm N is extended inwardly past the fulcrum pin, this extension being the short arm *n* of the lever (N *n*), and to it is fastened a 100

knife Q by means of one or more small bolts n' . The short arm o being an extension of the other lever arm O (the two parts forming the lever O o), is likewise provided with a 5 knife R fastened thereto by one or more bolts o' . The lever N n, the cross-bar P, and the lever O o form what I call the double lever N n, P, O o, which, as before stated, is pivotally fastened to the top of the slotted slide 10 M, by means of a nut m and bolt m' , as before stated, and as shown in Figs. 1 and 2. The slotted slide M is provided with two slots m^2 m^2 through which latter bolts m^3 m^3 pass, having their screw-threaded ends fastened 15 into the platform A, as shown in Figs. 2 and 4, the enlarged heads of the bolts m^3 m^3 serving to hold the slide closely up against the end of the platform A and yet permit it freely to move back and forward as it rests upon 20 the bolts. The reciprocatory movements of this slotted slide M are imparted by a hand lever S, said lever having a handle s, a rock-bar or rock-rod S' passing through two collars or boxes s^2 bolted fast under the base of the platform A, as shown in Figs. 2 and 4, the end of the rock-bar nearest the slide M being a turned-up slotted arm s^3 , the slotted arm s^3 , by means of its slot s^4 , affording a sliding bearing for the pin or bolt m^4 projecting from 25 the side of the slide M, to work in.

A disk gage T is adjustably secured by means of a slot t and a headed screw bolt t' upon the top of the platform A, the forked end near the flange I carrying an iron roller 30 t^2 provided with short journals working in journal bearings in the forked end projections. This roller t^2 works inside the disk L and flange I and near the knife R, and is for the purpose of firmly pressing against and 35 holding the edge of the disk L so that it shall be smooth or regular as it comes to the knife. Either knife Q or knife R, whichever may be used, may be readily adjusted upon the platform A, as various circumstances may 40 require. Where a large disk is being sharpened the roller t^2 could obviously be more advantageously used farther from the axis of the shaft H carrying the disk than when a disk of a much smaller diameter is being 45 sharpened, and hence the position of the roller t^2 must be in accordance with the particular requirements of the case. A guard bar T' is bolted to the top of the platform A as shown in Figs. 1 and 4, beneath which 50 the lever arm N works. The knives Q and R, that serve to do the cutting or shaving of the revolving disk in sharpening the same, are made preferably of silver steel and are attached to the short lever arms n o of the 55 levers N n, O o, in such a manner that they strike the revolving disk at an angle of about forty-five degrees to the plane of the disk's rotation. They cut the disk and do not scrape it.

In some cases files or other implements or 60 articles having suitably hard and rough abrading surfaces might be employed as substitutes for the knives, when it should be desired to

file or grind the sides of the disk at its edge to bevel and sharpen said disk, but I prefer to use for this purpose the knives as above 65 stated.

The operation of the machine is as follows: The attendant takes hold of the handle s of the lever S and rocks said lever in its bearings, and by means of its short slotted arm s^3 , and its connection with the slide M, moves the latter to the desired position for holding the knives in readiness to be applied by the double-lever mechanism. The attendant, if relying on his own manual power to run the 80 machine, stands in front of it, and with his right hand grasps the handle c on the fly-wheel C, and turns said wheel and its shaft F and thereby the small spur wheel E and through it the large spur wheel G and its 85 shaft H, which latter rotates the disk clamp and its tightly held disk L. The attendant then applies one or the other knives to the rotating disk, by seizing by his left hand, the handle n^2 of the lever N n. Moving said 90 handle to the left applies the knife Q to the rotating disk L, said knife being carried on the short arm n of the lever N n, and moving said handle to the right applies the knife R carried on the short arm o of the lever O o, 95 the cross-bar P serving to communicate the movement of lever N n to lever O o. In other words, standing with face to disk the attendant by moving the arm N of the main lever N n (of the double lever N n, P, O o) to the 100 left, puts the left knife Q against the left side of the disk, and moving said lever arm N to the right puts the right knife R against the right side of the disk. But one knife cuts at a time. It is obvious that a belt may be 105 applied to the pulley wheel D, and power from steam, or other motor power mechanism, be used to rotate the shafts and the disk.

I do not wish to be limited to the precise construction of parts as described and shown, 110 as the same may be variously modified without departing from the essential features of my invention.

I claim—

1. In a disk sharpener, the combination with 115 a supporting frame and a rotary disk-carrying shaft mounted thereon, of a slide also mounted on said frame and movable toward and from said shaft in a direction transverse to the longitudinal axis thereof, and one or more sharpening appliances pivotally mounted on said slide and movable toward and from the edge or edges of the rotating disk to be sharpened.

2. In a disk sharpener, the combination with 120 a disk-carrying shaft and means for rotating the same, of a movable sharpening device to be pressed against one side of the disk to be sharpened, and a gage secured to the table of the machine and arranged to bear against the 125 other side of the edge of the disk.

3. In a disk sharpener, the combination with 130 a supporting frame and a rotary disk-carrying shaft mounted thereon, of two levers pro-

vided with sharpening devices arranged to be brought into contact with the opposite sides of the edge of a disk carried by said shaft.

4. In a disk sharpener, the combination with 5 a supporting frame and a rotary disk-carrying shaft mounted thereon, of two connected levers mounted on a common pivot and having their shorter arms provided with sharpening devices arranged to be alternately brought 10 into contact with the opposite edges of the disk to be sharpened.

5. In a disk sharpener, the combination with 15 a supporting frame and a rotary disk-carrying shaft mounted thereon, of two levers suspended by said supporting frame and having their shorter arms provided with sharpening devices, and a rigid link or cross-bar connecting the longer arms of said levers, whereby the said sharpening devices are held separated 20 from each other but are adapted to be alternately brought into contact with the opposite sides of a disk to be sharpened.

6. In a disk sharpener, a slide carrying a 25 double lever provided with knives, in combination with a shaft carrying a clamp for holding a disk, and means for rotating said shaft, substantially as and for the purpose described.

7. In a disk sharpener, a double lever mechanism the short lever arms thereof provided 30 with knives and supported on a slide, in com-

bination with a rotary shaft carrying a disk clamp, substantially as and for the purpose described.

8. In a disk sharpener, the combination with 35 a supporting frame and a rotary disk-carrying shaft mounted thereon, of a slide also mounted on said supporting frame and movable in a plane transverse to the longitudinal axis of said shaft, a lever handle for advancing and retracting said slide, and one or more 40 levers pivotally mounted on said slide and provided at their forward ends with sharpening devices.

9. In a disk sharpener, the combination with 45 the table A, of the disk-carrying shaft H mounted thereon, a driving shaft geared to said shaft H, the slide M movable toward and from said shaft H, and the sharpening appliances carried by said slide.

10. In a disk sharpener, the combination 50 with the table A, of the disk-carrying shaft H mounted thereon, a driving shaft geared to said shaft H, the slide M movable toward and from said disk-carrying shaft, the sharpening appliances carried by said slide, and the disk- 55 gage T adjustably attached to said table.

HEZEKIAH CASEY.
